ARCHIBALD DAVIS, OF SCHENECTADY, NEW YORK.

FAULTY-CABLE LOCALIZER.

1,331,051.

Specification of Letters Patent. Patented Feb. 17, 1920.

Original application filed May 31, 1912, Serial No. 700,667. Divided and this application filed July 25, 1913. Serial No. 781,214.

To all whom it may concern:

Be it known that I, ARCHIBALD DAVIS, a citizen of the United States, residing at Schenectady, county of Schenectady, State 5 of New York, have invented certain new and useful Improvements in Faulty-Cable Localizers, of which the following is a specification.

My invention relates to the localizing of 10 faults developed on transmission lines and to apparatus particularly adapted for this work, although the apparatus I have shown and described is not limited in its applicability to this work alone.

15 My present application is a division of an application filed by me May 31st, 1912, Serial No. 700,667, faulty cable localizer, and relates particularly to my novel type of time limit device or relay used in connection with each localizer relay.

20 In carrying out my invention, of indicating upon which feeder or cable a fault occurs, I use a device which I desire to call a localizer. The localizer consists of a set 25 of interconnected relays, one relay being provided for each feeder or cable. These relays, which I desire to call localizer relays, are of a type of construction consisting of two coils each, the pulls of each 30 coil of the pair being balanced against each other, the only relay operating being the one in which an unbalancing occurs. When, therefore, an unbalancing occurs upon any feeder due to a ground thereon, 35 an unbalancing is also produced in the relay corresponding to this feeder and it is operated to suitably indicate this faulty feeder.

Since there are certain abnormal conditions occurring on transmission lines at 40 various times, which conditions are similar in their action to the disturbances caused by the faults which I desire to locate, but which exist for shorter periods of time, such as momentary surges, I provide a time 45 element device as a part of each localizer relay which delays indication of the abnormal condition until that condition has persisted for a certain definite period of time. Each localizer relay with its time element 50 device forms a unit, one unit being provided for each feeder. By properly adjusting the time element device the localizer will therefore indicate a fault only. There may be other pieces of apparatus also

attached to the transmission system, as for 55 example, an arcing ground suppressor, which operate only after a certain period of time, and the actuation of which prevents the actuation of my localizer. The period between the length of time during 60 which an abnormal condition which I do not care to localize, may exist, and the period of time required by the outside apparatus to operate may be very short, and one of the great advantages of my invention lies in 65 the ability of the time element device to differentiate between these two periods. I have found that the time element device of my localizer can be constructed to restrain indication on the occurrence of abnormalities persisting for not more than one-fifth 70 of a second, and still allow operation in less than one-fourth of a second on the occurrence of a fault.

Figure 1 shows diagrammatically a three 75 phase system of distribution including three feeders connected to the same bus bars and connected to a localizer which, however, in this figure are only shown in part. Fig. 2 shows diagrammatically one construction of 80 a localizer relay involving my invention and embodying my novel type of time limit device.

In Fig. 1, the generator 1 is connected to the bus bars 2; to these bus bars are connected three feeders. I have provided a localizer comprising localizer relays, 3, 4, 5, one for each of the feeders shown, which on the occurrence of a fault on any one of the three feeders indicates the feeder on which 90 the fault occurs. The part of each localizer relay which I have shown in Fig. 1 comprises a magnetic E-shaped core on the two outer legs of which are mounted coils or solenoids 6 and 7. An armature 8, balanced 95 and pivoted at 9, is subject to the attractions of both solenoids which tend to move it in opposite directions. A spring 10 may be provided to hold the armature against the stop 11, which it is desirable to use, although neither the spring nor the stop are absolutely necessary. I desire that the movement of the armature 8, in response to a stronger attraction of the solenoid 7, should be indicated, but do not care to indicate the supremacy of solenoid 6 over 7. For this purpose, I have provided the contact 12 which cooperates with the armature,

as will be apparent from Fig. 2, to complete a circuit for actuating the indicator. Since it is not necessary for the armature to respond to the greater attraction of solenoid 6, it is well to use the stop 11 and spring 10 to maintain the armature in such a position that it may be readily actuated on the supremacy of solenoid 7.

By providing a plurality of solenoids 10 for controlling a single armature, the various solenoids may be connected to different feeders and be energized thereby; under normal conditions the armatures of the localizer relays will remain at rest and in such 15 a position that no indication is given, the localizer being designed and constructed with this object in view. On the occurrence of abnormal conditions, however, the feeder, on which the fault has occurred, will energize 20 the solenoid of the localizer relay connected thereto to a different degree than will the other feeders energize their solenoids. There will then be a responsive action on the part of at least one of the 25 armatures to give an indication. In this particular case, I have connected the solenoids to the feeders in such a way that under normal balanced conditions on the feeders, no current will be supplied to the solenoids, and 30 have arranged the solenoids and armatures of the localizer relays so that one armature and only one will give an indication when the solenoids attached to one feeder are more 35 strongly energized than the other. The connection may be made through three 40 transformers similar to instrument transformers connected as shown, the result being the production of zero electromotive force in each of the connections to the solenoids during such times as the currents 45 through the primaries of each of the groups are balanced, as under the normal operation of the system they will be. The localizer relays are made independent of load current 50 by connection with the current transformers as shown. As long as the current that flows out one phase of the feeder, at any instant, flows back over either one or both of the other phases, the currents in the current 55 transformer secondaries do the same. Therefore, there is no current in the localizer relay and this condition is true no matter how unbalanced the load current may be. This particular connection may be 60 replaced by others which perform substantially the same functions.

We will first suppose that the feeders are 65 of the same electrostatic capacity. Under this condition the occurrence of a ground on one of the feeders will produce an unbalancing in each group of transformers but there is a greater unbalancing in the group attached to the grounded feeder than in any other, and hence the current supplied to the 70 solenoids attached to the grounded feeder

will be greater than the current supplied by any other feeder. Also the unbalancing in and hence the current supplied by the other groups of transformers will be equal. The explanation why this unbalancing takes place in this manner is not simple, due to the many factors involved, but experiment has shown that such unbalancing does occur. For the purpose of illustration, we may suppose that a ground has 75 occurred at the point 13. The current, therefore, supplied to the solenoids on the localizer relays 3 and 5, which are attached to this feeder, is greater in value than the current supplied to the other solenoids. 80 The currents supplied to the solenoids attached to each of the other feeders are equal in value to each other. The result of this is that the solenoid 7 of the localizer relay 85 3 and the solenoid 6 of the localizer relay 5 exert more attractive force on their respective armatures than do the opposing coils. The armature 8 of the localizer relay 3 therefore moves into engagement with the contact 12. The armature of the localizer relay 5 does not move on account of its engagement with the stop 11. Should no stop have been provided, the armature then moves downward on the left-hand side without actuating the indicating device, 95 since the armature does not come into engagement with the contact 12. As for the armature 8 of the localizer relay 4, it remains in its balanced position shown in the drawing, since the attractive forces of the 100 solenoids 6 and 7 are equal. The ground 13 will, therefore, operate the localizer and produce an indication upon which feeder the fault has occurred by means of its localizer relay 3. It will be noticed that there 105 is a localizer relay for each feeder the armature of which will respond to a ground on its feeder while the other armatures of the other localizer relays are held in their balanced position, or at least away from their 110 contact 12. This is due to the fact that taking the localizer relays in order, the solenoid 6 of the first localizer relay is in series with the solenoid 7 of the second relay and attached to one feeder, the solenoid 6 of 115 the second relay is in series with solenoid 7 of the third localizer relay and attached to another feeder, this system of connections continuing until the last localizer relay is reached when the solenoid 6 of that relay 120 is connected in series with the solenoid 7 of the first localizer relay and to the last feeder. I have shown, for purposes of illustration, the application of my localizer to a distribution system comprising three 125 feeders but it is understood that by adding a relay for each feeder that my localizer is applicable to a system comprising any number of feeders.

Seldom, if ever, are all the feeders of the 130

same electrostatic capacity. The amount of current supplied by each group of transformers on the occurrence of a ground elsewhere than on the feeder to which that group of transformers is connected is proportional to the electrostatic capacity of that feeder. Therefore, should an armature be under the control of a solenoid 6 attached to a feeder of small electrostatic capacity and a solenoid 7 attached to a feeder of large electrostatic capacity, and should a fault occur elsewhere on the system than on either of those feeders, nevertheless the solenoid 7 would predominate and produce an actuation of the armature 8. This difficulty may be overcome in various ways, as by properly proportioning the windings of the transformers variously locating the armatures and coils relatively, and otherwise. I prefer, however, to make the numbers of turns on the various solenoids inversely proportional to the electrostatic capacities of the feeders to which they are attached. Thus the solenoids attached to a feeder of small electrostatic capacity will have more turns than the solenoids attached to a feeder of a greater electrostatic capacity. When such provisions are made, the occurrence of a fault elsewhere than on the feeders will produce equal attractive forces on the armatures. Stated otherwise, equal abnormalities in the various feeders will produce attractive force by the various solenoids inversely proportional to the electrostatic capacity of the feeders to which the solenoids are respectively connected.

As has been before noted, it is desirable to make a localizer relay which will give an indication of an abnormality only after the continuance of that abnormality for a certain definite period of time, and also to produce the actuation of such indicator within a given period of time. Obviously the localizer should be able to work within very narrow limits. I have produced a localizer which in its complete form includes a time element device capable of the fine adjustment necessary, and although I have termed the complete device a localizer relay, it will be understood from the description that neither the complete device nor any component part is limited in its applicability to the particular application which I have made. I propose to depend upon inertia to determine the period which must elapse between the occurrence of a condition and the actuation of the indicator. I propose to provide an indicating mechanism with substantial inertia and to provide a device tending to actuate the indicator with a substantially constant force. If then the condition for allowing the actuating of the indicator continues for a certain period of time, the inertia of the indicator will be overcome by its moving device and the in-

dication given. Should, however, the condition have changed within that period, the further actuation of the indicator will be prevented, and the whole returned to its original position if desired. The indicator 70 may be the arm 14, but I have shown in this case this arm completing a circuit through the lamp 30 which thus becomes the indicator proper; this circuit is completed when the arm 14 is brought into engagement with 75 the contact 15. It should be understood that by the term "indicator" I do not intend to limit my invention to a visual or audible indicator but that I use the term broadly and that it may include means for actuating 80 switches or other devices as desired. The arm 14 is mounted on the rotatable member or driven shaft 16, one end of which is carried by the bearing 17, and the other end of which is carried in a bearing in the end 85 of the rotatable member or driving shaft 18. The shaft 18 is supported by the bearing 19. Upon the rotatable member or shaft 16, I have mounted a fly wheel 20 of a size and weight to give the desired inertia to the system. I have provided a spring 21 having one end 22 attached to the shaft 16. This spring may be put under tension, and its other end may be fixed as desired, but I prefer to attach the other end 23 to the shaft 90 18 as shown. The spring 21 normally tends to rotate the shaft 16 and thereby the indicator arm 14 and fly wheel 20. Such rotation is normally prevented by the abutments 24 and 25, one of which is attached to the 95 shaft 16, the other of which stands in its path until moved therefrom on the occurrence of the condition which it is desired to indicate. When the abutment 25 is suddenly removed from the path of the abutment 24, the shaft 16 is turned by the spring 21 and the indicator arm 14 moved thereby. To move the arm 14 a certain definite distance, however, requires a certain period of time, due to the fact that the inertia of the fly wheel and the whole system must be overcome by the moving device, the spring 21. If, therefore, the abutment 25 is removed from the path of the abutment 24 and kept from said path for the given 105 110 period of time or longer, the indicator arm 14 will be moved to the proper extent to give an indication. If on the other hand, the abutment 25 is returned to the path of the abutment 24 before the elapse of this 120 time, a further actuation of the indicator arm 14 will be stopped. In the particular construction I have shown, the abutment 25 is mounted on the shaft 18 which is controlled by the armature 26 connected by the 125 arms 27 to that shaft. When the solenoid 28 is energized by the completion of the circuit therethrough, as by the engagement of the armature 8 with the contact 12, the armature 26 is attracted and the shaft 18 ro- 130

tated thereby. The movement of the armature 26 is sufficient to remove the abutment 25 to such an extent that the shaft 16 is allowed to rotate to move the indicating arm 14 to the indicating position. However, should the armature 26 be released by the deenergization of the magnet 28 by the breaking of the circuit at the contact 12, the abutment 25 will be brought back into the path of the abutment 24 and the shafts 16 and 18 and the parts attached thereto will be returned to the original position shown in the drawing by the spring 29. The spring 29 is intended to be strong enough to return all parts to their original positions from any point of their travel substantially instantaneously, irrespective of the inertia of the fly wheel 20 and the rest of the system. As before mentioned, I have constructed such a device as this which would operate the indicating arm 14 to its indicating position, whenever the armature 8 was held in engagement with the contact 12 for a period longer than one-fifth of a second, the indicating arm 14 moving to this position within one-fourth of a second. The device so constructed is reliable in its operations and capable of repeating this performance within the given period of time an indefinite number of times.

In order to make the indicating arm 14 reveal its actuation by means of the lamp 30 and to continue the illumination on the retreat of the indicating arm 14 from the contact 15, I have provided the apparatus and connections shown. Thus as the arm 14 engages with the contact 15, a circuit is completed through the electromagnet 31, the lamp 30 and the switch 32. The energization of the electromagnet now causes the attraction of the armature 33 which completes another circuit through the armature 33, electromagnet 31, lamp 30 and switch 32. When the arm 14 leaves the contact 15, the light is not extinguished, but will be continued until the circuit through the armature 33 is broken, as may be done manually at the switch 32.

It will, of course, be understood that a number of the features shown and described are optional, and that the form and operation of others may be changed without substantially departing from the invention herein disclosed.

What I claim as new and desire to secure by Letters Patent of the United States, is:—

1. A relay including an armature, a solenoid controlling said armature, a normally tensioned spring, means operated by said armature for releasing the tension of said spring, means for returning said first mentioned means to its original position when released by the armature, and mechanism moved by said tensioned spring having substantial inertia.

2. A relay including an armature, a solenoid controlling said armature, a normally tensioned spring, means operated by said armature, for releasing the tension of said spring, mechanism having substantial inertia moved by said tensioned spring, and means for returning said first mentioned means and the mechanism from any point of their travel to their original position when released by said armature.

3. A relay including an armature, a solenoid controlling said armature, a normally tensioned spring, means operated by said armature for releasing the tension of said spring, mechanism having substantial inertia moved by said tensioned spring, and means for substantially instantaneously returning said first mentioned means and the mechanism from any point of their travel to their original position when released by said armature.

4. In a relay the combination with two rotatable members, means for rotating one of said members but normally held inoperative, means for rotating the other of said members in response to a predetermined condition, means responsive to the rotation of the other of said members for rendering said first mentioned means operative, a circuit controlled by the rotation of said first mentioned means, and an inertia device for introducing a time delay between the rotation of the other of said members and the control of said circuit.

5. A relay comprising two rotatable members substantially in alignment, means for rotating one of said members upon the occurrence of a predetermined condition, means normally tending to rotate the other of said members but prevented from doing so until said first mentioned member is rotated, a circuit controlled by the rotation of said other member, and means for introducing a time interval between the rotation of said first mentioned member and the operation of said circuit.

6. A relay comprising two separately actuated members substantially in alignment, means for rotating one of said members upon the occurrence of a predetermined condition, means for rotating the other of said members but normally held inoperative until the rotation of said first mentioned member, contacts controlled by the rotation of said other member, and means for introducing a time interval between the rotation of said first mentioned member and the operation of said contacts.

7. A relay comprising two rotatable members, a solenoid, an armature controlled by said solenoid for rotating one of said members, a spring for returning said member to its initial position, independent means normally tending to rotate the other of said members but held inoperative until

the rotation of said first mentioned member, and a device having substantial inertia operatively related to said other member.

8. A relay comprising two rotatable members substantially in alinement, a solenoid, an armature controlled by said solenoid for rotating one of said members, a normally tensioned spring released by the rotation of said first mentioned member to 10 rotate the other of said members, a movable contact carried by said other member, a fixed coöperating contact, a member having substantial inertia mounted on said other member for introducing a time interval between the rotation of said first mentioned member and the closing of said contacts.
9. A relay comprising a driving and a driven shaft substantially in alinement, electromagnetic means for rotating said 20 driving shaft, a spring normally tending to rotate said driven shaft, a stop normally holding said spring inoperative but movable in response to the actuation of said driving shaft to render said spring opera-

tive, a circuit controlled by the rotation of 25 said driven shaft, and a retarding device for delaying the control of said circuit a predetermined interval after the rotation of said driving shaft.

10. A relay comprising two rotatable 30 members, a solenoid, means controlled by said solenoid for producing a rotation of one of said members, means for rotating the other of said members, in response to the rotation of said first mentioned member, a 35 fixed contact, a coöperating contact movable into engagement with said fixed contact by the rotation of said other member, and a mechanism having substantial inertia operatively related to said other member for 40 retarding the rotation of said member.

In witness whereof, I have hereunto set my hand this 24th day of July, 1913.

ARCHIBALD DAVIS.

MARGARET E. WOOLLEY.

Correction in Letters Patent No. 1,331,051.

It is hereby certified that Letters Patent No. 1,331,051, granted February 17, 1920, upon the application of Archibald Davis, of Schenectady, New York, for an improvement in "Faulty-Cable Localizers," were erroneously issued to the inventor, said Davis, whereas said Letters Patent should have been issued to *General Electric Company, a corporation of New York*, as assignee of the entire interest, as shown by the records of assignments in this office; and that the said Letters Patent should be read with this correction therein that the same may conform to the record of the case in the Patent Office.

Signed and sealed this 4th day of May, A. D., 1920.

[SEAL.]

Cl. 200—97.

M. H. COULSTON,

Acting Commissioner of Patents.
